(57) **CLAIM**

The ornamental design for an e-cigarette case, as shown and described.

DESCRIPTION

FIG. 1 is a perspective view of an e-cigarette case showing my new design;

FIG. 2 is another perspective view of an e-cigarette case as in FIG. 1 showing the case in an open configuration;

FIG. 3 is a front view thereof;

FIG. 4 is a back side view thereof;

FIG. 5 is a right side view thereof;

FIG. 6 is a left side view thereof;

FIG. 7 is a top view thereof; and,

FIG. 8 is a bottom view thereof.

In the drawings, the broken lines showing an e-cigarette illustrate environment and form no part of the claimed design.
